Primary Examiner — Nathan M Johnston(57) **CLAIM**

The ornamental design for a “robotic catheter manipulator”, as shown and described.

DESCRIPTION

FIG. 1 is a top, front, and left side perspective view showing our new design for a robotic catheter manipulator.

FIG. 2 is a left side view of the robotic catheter manipulator of FIG. 1.

FIG. 3 is a right side view of the robotic catheter manipulator of FIG. 1.

FIG. 4 is a front view of the robotic catheter manipulator of FIG. 1.

FIG. 5 is a rear view of the robotic catheter manipulator of FIG. 1.

FIG. 6 is a top view of the robotic catheter manipulator of FIG. 1; and,

FIG. 7 is a bottom view of the robotic catheter manipulator of FIG. 1.

The broken lines show portions of the robotic catheter manipulator that form no part of the claimed design.
